DESIGN FOR HAIR-CUTTING SCISSORS

Joseph A. N. De Requesens, New York, N. Y., assignee of one-half to Frank Lozano, New York, N. Y.

Application July 10, 1940, Serial No. 93,541

Term of patent 7 years

To all whom it may concern:

Be it known that I, Joseph A. N. De Requesens, a citizen of the United States, residing at New York, in the county of New York and State of New York, have invented a new, original, and ornamental Design for Hair-Cutting Scissors, of which the following is a specification, reference being had to the accompanying drawing, forming part thereof.

I claim:

The ornamental design for hair-cutting scissors, as shown.

JOSEPH A. N. DE REQUESENS.
